UNITED STATES PATENT OFFICE.

SIMON W. WARDWELL, OF PROVIDENCE, RHODE ISLAND.

WINDING-MACHINE.

1,093,900.

Specification of Letters Patent. Patented Apr. 21, 1914.

Application filed October 3, 1910. Serial No. 585,059.

To all whom it may concern:

Be it known that I, SIMON W. WARDWELL, a citizen of the United States, residing at Providence, in the county of Providence and State of Rhode Island, have invented a new and useful Improvement in Winding-Machines, of which the following is a specification.

My invention is an improved winding machine, the purpose of the improvement being to produce a machine possessing unusual productive capacity per winding unit, so compact as to substantially increase the productive capacity of the floor space occupied and so automatic that the machine operator may attend a greater number of these more productive winding units with less exertion and fatigue than under the now usual conditions of operation and production. The novel means whereby these beneficial results are secured are fully disclosed in the following specification and the accompanying drawings which show respectively—Figure 1 a perspective view showing the general arrangement; Fig. 2 a section through the axis of one of the spindles and to the axis of the machine; Fig. 3 a view looking down upon the cap showing arrangement of gearing; Fig. 4 a view of one of the swinging frames swung away from the machine; Fig. 5 a section of Fig. 4 on the line $z-z$, and looking down; Figs. 6 and 7 details of Fig. 4; Fig. 8 a plan view looking down upon the machine, but with the cam 2, cap 24 and gearing removed; Figs. 9, 10 and 11 details of the tension and stopping devices; Fig. 12 a view sectional on line $y-y$ of Fig. 2; Fig. 13 a view sectional on the line $x-x$ of Fig. 12; Fig. 14 a detail of the tension, sectional on the line $u-u$ of Fig. 11 looking in the direction of the arrow t .

The machine Fig. 1 consists primarily of a plurality of winding units disposed about a single central cam 2 which actuates all of the reciprocating guides 3, in proper relation with winding spindles 4, on which the yarn is wound in self contained packages 5, one of which is indicated. The yarn is drawn from supplies 6 through tensions 7, 8 and 9. The devices indicated, with their correlated parts and connections are mounted on a bed 10, beneath which a shaft 11 is mounted in bearings 12, 12, 12. The machine is driven by means of a pulley 13 on said shaft, and the driving action is transmitted through the

gears 14 and 15 to the mechanical organism of the machine by means to be detailed later.

The winding units including their supplies and tensions are all preferably secured to a rotatable table 17 which surmounts the bed 10 and rides on antifriction wheels 16, 16, 16, and has also central bearing in said bed 10. See also Fig. 2, and Fig. 13.

Each winding unit comprises a stand 18, 65 with guiding means for the thread guide 3, and for the traverse slide 19 by which the guide is driven from the cam, a swinging spindle frame 20 hinged to the stand on which frame the winding spindle 4 is mounted with its friction wheel 21, means for stopping the winding action of the unit in case of breakage or exhaustion of the yarn supplied, and means to cause automatic revolution of the inactive unit, to present it to the 75 operator.

Referring to Fig. 2 which is sectional through one of the winding spindles 4, the gear 15 is mounted on a vertical shaft 22 which has a bearing in the hub 23 in the 80 table 17 and another upper bearing in the cap 24 which surmounts the cam 2 and is supported by and secured to steps 25 on the stands 18. (See Fig. 1 and Fig. 10.)

Immediately above and bearing by its hub 85 on the table 17, is the friction driving wheel 26, secured to the shaft 22, to rotate with it, to drive the friction wheels 21, and thereby the winding spindles 4. The friction wheels 21 are maintained in active engagement with the friction driving wheel 26 by the springs 27 extending between the stand 18 and the swinging frame 20—Figs. 1, 8 and 12. At the top of the shaft 22 is a gear 28 which through the train of gears 29, 30 and 31 rotates the cam 2 by the internal gear 32 which is secured within the rim of the cam. The gear 31 which works with the internal gear 32 is mounted on a shaft 33 for which a bearing 34 is provided in the cap 24. The intermediate gear 29 is mounted on a stud 35 for which alternative positions are provided in the location shown and at 37—Fig. 3—to admit change of the gears 28 and 30, to vary the number of turns by the winding 105 spindles per reciprocation of the thread guides. Such a change is shown by broken lines, an alternative train of gearing being indicated by broken lines at 28^a, 29^a and 30^a. Provision for changing the gear 30 is made 110 in the set screw 38 whereby the gear 30 is removably secured to its shaft 33, and like

provision is made for the gear 28. The cam 2 is of the usual cylindrical form with a helical groove extending half way around the cam in one direction, and then halfway 5 in the reverse direction so that one rotation of the cam causes one complete reciprocation of a thread guide.

Fig. 4 shows one of the swinging frames 20 swung back, away from the machine, 10 which is not an operative position but one employed to better show the arrangement of parts. The thread guide 3 is mounted on an arm 39 which in turn is mounted on a tube 40. The tube slides on a rod 41 which is secured in the bracket 18. Below the tube 40 on the rod 41, is a slidable member 19 which is termed the traverse slide, having a roll 43 in a stud 44 which roll engages and is acted upon by the cam 2 to reciprocate the traverse slide. A fin or guide 45 extends into a guide way 46 in the bracket 18, preventing rotation of the traverse slide Fig. 5. The traverse slide also has one side formed with a locking notch or ward 47 to which beveled 25 faces 48 and 49 lead from either end of the traverse slide Fig. 4 and Fig. 7.

Secured to the tube 40 is a spring 50, preferably through the intermediation of the block 51—Fig. 4. The extremity of the 30 spring is formed with a lateral projection or latch 52, offset with reference to the plane of the spring, as shown in Figs. 6 and 7, and it is this latch 52 which registers with and engages the ward 47 when the winding unit is 35 in operation. The block 51 also has a fin entering the guideway 46 to prevent the block from turning and to maintain the latch 52 in relation with the traverse slide 19. As the 40 form and arrangement of this fin is so obviously like the fin 45 of the traverse slide it is not detailed.

The operation of the winding unit is stopped by swinging the frame 20 away from the cam 2, sufficiently to disengage the 45 friction wheel 21 from the friction driving wheel 26. At the same time, the spring latch 52 is disengaged from the traverse slide to stop the reciprocation of the thread guide 3 by the wiper 53. The latter is secured to the 50 swinging frame 20, (see Fig. 4), and is so formed as to extend along the path of the traverse slide and during operation of the winding unit just behind the extremity of the latch 52, which extremity projects over 55 the side of the traverse slide. (Fig. 6.) In this position, the wiper 53 does not interfere with the engagement of the latch 52 with its ward 47.

When the operation of the winding unit is 60 stopped by swinging the frame 20 away from the cam 2 and from the friction driving wheel 26, the wiper 53 is shifted into position indicated by Fig. 7 where it disengages the latch 52 from the ward 47. The 65 wiper does not extend the full extent of the

path of travel of the traverse slide 19 but is preferably only a little longer than that member. Its extremities 54—54 are inclined to its main surface, so that, should the wiper be shifted forward by stopping of the winding unit to which it belongs, at a time when the traverse slide 19 is away from it, (as, for example, at one extreme or the other of its traverse), nevertheless, when the traverse slide 19 does return to the wiper 53, the latch 52 will encounter one or the other of the inclined extremities 54 of the wiper, and be disengaged by the latter from its ward 47, thus leaving the traverse slide 19 to move idly by action of the cam 2, without operating the guide 3.

When the unit is again started, return of the frame 20 toward the cam 2, to engage the spindle's friction wheel 21 with the friction driving wheel 26, withdraws the wiper 53 from the latch 52, permitting the latter to encounter one or the other of the inclined faces 48 or 49 of the traverse slide 19, up which face it rides and enters the ward 47, coupling the guide 3 with the reciprocating 90 traverse slide 19.

The swinging frame, normally held toward the cam 2 by a spring 27, is automatically moved away, to stop the winding unit, by the knock-off 55 which, by action of the 95 yarn being wound is maintained inactive while the yarn is intact and under tension. The knock-off 55 has an extremity with a working or dogging edge 57, which when it contacts with the surface of the cam 2 engages the latter frictionally whereby it is rocked and forces the frame 20 away from the cam 2 disengaging the spindle friction wheel 21 from the friction driving wheel 26. See B, Fig. 8. The knock-off is impelled to 100 thus engage the cam 2 by the end stop 58 which is rockable on the rod 59—Figs. 9, 10 and 11. The latter is secured in the tension bracket 60, and carries a bar 61 which also swings on the rod 59 by bearings 62 and 63 preferably formed by coiling the bar 61 about the rod 59. On the rod 59, opposite the knock-off 55 is a lever 64 having a forked arm 65 engaging the bar 61, an arm 66 that is connected by the connecting rod 67 with the arm 68 of the knock-off 55—Figs. 8—9 and 10—, and a counterweight 69 which tends to maintain the knock-off 55 away from the cam 2. The end stop 58 is so proportioned and related to the counterweight 69 as to 115 overcome the latter's action, when the end stop is dropped from its normal position. During winding, the end stop 58 is upheld by the yarn, but when the yarn breaks, or its supply is exhausted the end stop 58 drops, 120 engages the bar 61, overcomes the tendency of the counterweight 69, and forces the knock-off into engagement with the cam 2 as described.

The cam 2 rotates continuously without 130

stopping and continued contact of the knock-off 55 with it would be detrimental, either scoring the cam 2 or wearing the working or "dogging" edge 57 of the knock-off, or both. It is therefore necessary that the frame 20 be yet further moved so as to withdraw the knock-off from the cam 2. This is accomplished by the knock-off cam 70 which acts as follows—Fig. 4. The member 70 is connected with the handle rod 71 by two collars 72 and 73 located on either side of the projection 74 of the knock-off cam 70, in which projection the rod 71 has a bearing. The rod 71 also has bearings 75 and 76 in the frame 20. A compression spring 77 reacting against the bearing 75 and acting upon the collar 72 impels the knock-off cam 70 to act downward. This downward impulse is opposed by a seat or shoulder 78 preferably on the stand 18 which during operation of the winding unit abuts and supports the bottom surface 79 of the knock-off cam 70. Adjacent the surface 79 is an inclined cam surface 80 which when the surfaces 78 and 79 are disengaged acts, under impulse of the spring 77, against the shelf 78, moving the spindle frame yet farther, and withdrawing the knock-off 55 from contact with the cam. See C—Fig. 8. Concurrently, the member 70 acts upon the winding spindle 4, through the brake 81, to arrest its movement due to momentum. An arm 82, of said knock-off cam 70, engages with its forked extremity, the neck 83 of the brake 81, which engagement incidentally prevents the knock-off cam 70 from turning either with or about the rod 71. When the unit is operating, the knock-off cam 70, supported by the shelf 78, upholds the brake 81 by its peripheral shoulder 84. The brake 81 is a non rotatable clutch, carried on the winding spindle 4 and having a taper friction surface 85 which engages a corresponding surface 86 of the friction wheel 21—Fig. 2. A radial forked lug 153 engages the rib 87 of the frame 20, preventing the brake from rotating with the winding spindle—Fig. 12.

When the operation of a winding unit is to be started, the knock-off cam 70 must be raised to release the frame 20 to the action of the spring 27, which returns the frame toward the cam 2 to reengage the friction wheel 21 with the friction driving wheel 26, and the knock-off 55 must be withdrawn to a position where it cannot obstruct such return. This is accomplished by the arm 88 secured to the rod 71, which arm extends through the opening 89 in the frame 20—Figs. 1, 4 and 8. The bottom edge of this opening is inclined at 90—Fig. 1—and contacts, as a lifter cam, with the arm 88. When the arm 88 is at the lowermost position, the handle portion 91 of the rod 71 lies close to the stand 18, against the edge 92, as

shown by full lines at C in Fig. 8. It is normally maintained in that position by the spring 77 which acts torsionally on the rod 71—Fig. 4. One extremity 93 of the spring 77 enters the collar 72, and the other extremity 94 lies flat against the frame 20. By turning the handle 91 in the direction of the arrow—Fig. 8—in opposition to the torsional tendency of the spring 77—the arm 88 is caused to ride up the lifter cam 90, thereby raising the rod 71 and with it the knock-off cam 70, raising the bottom 79 of the latter above the shelf 78, and yielding the frame 20 to the action of the spring 27. As the handle 91 turns—see C Fig. 8, the downward extremity of the arm advances behind the curved offset 95 of the arm 68 of the knock-off 55, locking it, as shown by the broken lines, against engagement with the cam 2, while the swinging frame 20 resumes its normal position with the friction wheel 21 in contact with the friction driving wheel 26. The instant the friction wheel 21 makes such contact, it rotates the winding spindle and tightens the yarn, which as previously explained, raises the end stop 58 and relinquishes the knock-off 55 to the action of the counterweight 69 which acts to withhold the knock-off from the cam 2. Then the handle is released, and returned by the spring 77 to its normal position against the edge 92 of the stand 18—D, Fig. 8. When the handle 91 returns to the edge 92, it remains at the height to which it has been elevated by the lifter cam 90, maintained there by the knock-off cam 70 resting on the seat 78.

Upon stopping the operation of a winding unit, it is revolved to a predetermined position by the constantly rotating cam 2 which, acting through frictional resistance of the traverse mechanism, propels the table 17 and supported winding units. The table 17 is constantly subject to this rotative tendency or impulse and such rotating tendency is normally prevented by the detent 101, which is mounted on the under side of the table, and engages one of a sequence of position pins 102—103—104, &c., there being as many position pins as there are winding units—Figs. 8 and 12. Each pin is formed with a square edged abutment which is engaged by the surface 105 of the detent. An arm 106 of the detent has a projection 107 extending upward through an aperture 108 in the table 17 into engagement with the ring 109 which is rotatably mounted on the top of the table 17, seated on a suitable shoulder. The edge of the ring 109 is formed with a shoulder 110 engaging the projection 107 of the detent 101, and with as many other shoulders 111—112—113 &c. as there are winding units in the machine. These other shoulders face oppositely to the shoulder 110, so that pressure 130

against any one of them causes the shoulder 110 to act on the detent 101 to release it from whichever position pin 102—103—104 &c. it then engages. The detent 101 is maintained 5 in lock with its position pin by the tension spring 114 extending from the anchorage 115 in the table 17 to the arm 106 of the detent. As the projection 107 from this arm acts on the ring 109, the effect of the 10 spring's action is to maintain the ring in normal position which latter is determined by the limit pin 116 and the slot 117 into which it projects. Obviously, the limit pin 116 serves to limit the extent of engagement 15 of the detent 101 with its position pin.

Secured to each frame 20 is an arm 118 having a hooked extremity 119 which engages the ring 109 by one of the shoulders 111 or 112 or 113 &c. When the frame 20 20 is swung away from the cam 2 to stop the winding unit's operation, the arm 118 swings with it, moving the ring 109, and through it the detent 101, disengaging it from its position pins. The table 17 then 25 revolves under impulse of the cam 2 as described, until stopped.

On the bed 10 is a stop 154 located at such a height as to encounter the bottom of the rod 71 which when at its lowest position 30 is projected through the bearing 76 of the frame 20 as a bolt. Therefore, whenever any winding unit stops operation, it is revolved until arrested by the stop 154. The latter is supported by a tongue 120 in 35 the groove 121 on the bed 10, and can be set at any desired position, being removably secured by the crew 122—Figs. 1, 12 and 13.

The tension brackets 60 are secured by screws to projections 123 of the stands 18,— 40 Figs. 1, 10 and 11—and each is interlocked with its neighbor, as shown in Figs. 1—10—11 (plan view) preferably by screws 124—125. Mounted on the brackets are polished disks 126—127, housed in the casing 128—Fig. 14. The latter has a hub 129 in which a pin 130 is rotatably mounted. On the pin a ratchet 131 is secured, and the portion of the pin which projects outward from the ratchet is flattened on opposite sides. 45 The two disks are made, each with an axial hole corresponding in shape to the oppositely flattened pin so that as the pin turns, the disks turn with it thus distributing the wear of the yarn on the disks, preventing 50 grooving, which would occur were the disks non-rotative and the yarn drawing constantly over one portion of their surface. A thrust piece 132 abuts the outer disk against which bears one arm of the lever 55 134, which is preferably formed of wire with coiled hubs 135 and 136 bearing on the pin 137 mounted in lugs 138 and 139 of the tension bracket—Fig. 10. On the horizontal arm 140 is a weight 141 which, acting

through the lever 134, presses the tension 65 disks 126—127 together, upon the yarn.

Rotation of the pin and disks is secured by movement of the pawl 142 which hangs in a stirrup 143, its hooked or acting end resting on and engaging the teeth of the 70 ratchet 131—Fig. 11. Operatively connected with the stirrup 143, by a connecting rod 144 is a lever 145 fulcrumed at 146 to the tension bracket. The lower end of the lever 145 is formed with a wiper 147 which 75 is held toward the traverse slide 19 by the spring 148, but limited in its approach thereto by the stop pin 149. As the traverse slide reciprocates, it encounters and oscillates the lever 145 by a cam portion 150 80 which has two oppositely inclined faces 151—151. Thread is introduced to the tensions through the slot 152 cut through the side of the casing 128—Fig. 14.

My improved winding machine is operated 85 as follows: The yarn supplies of a unit having been filled, the yarns are led to their respective winding spindles. I have shown in Fig. 1 provision for winding one end at a time (at the left) and for winding four 90 ends at a time (in front). In case one end is wound, the yarn is led through the guide 9 directly to the winding spindle. In case four ends are wound, the yarns are led through the guide 8 first and thence through 95 the guide 9 to the spindle. The reason for the extra deflection in the case of a plurality of yarns is to establish their converging point so there shall be equal tension on each yarn, and to increase the running distance 100 to the spindle so that in case of breakage of a single yarn, the broken end may not run into the package. Each unit is started by turning the handle 91 as described, which permits the frame 20 to swing to the cam 2, 105 engaging the friction wheel 21 with the friction driving wheel 26 and permitting engagement of the guide traversing device with the cam. Turning the handle 91 also releases the winding unit from the stop 154, 110 permitting the table 17 to revolve and present another unit to the operator, the next unit being stopped by the encounter of its rod 71 with the stop 154. Thus the units are successively started all revolving as each 115 is started until stopped by the encounter with the stop 154, of the rod 71 of the next inoperative unit, until all are put in operation. When the last one has been started and released from the stop 154, all revolve 120 once more until the detent 106 encounters the nearest position pin 101. On breakage of a yarn or exhaustion of supply, the end stop 58 controlled by that yarn is released, 125 causing the knock-off 55 to act. This engages the cam 2, acting itself as a cam and forcing the frame 20 away from the cam 2. In swinging, the frame 20, through the arm

118 and the ring 109, shifts and releases the
detent 106 from its position pin, permitting
the table 17 to revolve and carry the inop-
erative unit to the operator, the rod 71, hav-
ing been projected as a bolt, to encounter
the stop 154. This action does not stop the
operation of any other unit, but all on which
the supplied yarn remains intact continues
winding. The operator pieces or replen-
ishes the yarn as the case demands and starts
the unit as before described.

Without limiting myself to the precise
form and arrangement of the components of
my invention, I claim;

15 1. In a winding machine, the combination
with a single cam, a plurality of winding
spindles arranged about the cam and trans-
mission connections between said spindles
20 and cam, of a plurality of winding guides
all actuated by the single cam, each guide
being independent of the others, and means
to disconnect the guides from the cam.

2. In a winding machine, the combination
with a single cam, of a plurality of winding
spindles arranged about the cam and trans-
mission connections between the spindles
25 and the cam, of a plurality of winding
guides all actuated by the single cam, each
guide being independent of the others, and
means to disconnect any one of the guides
30 from the cam.

3. In a winding machine, the combination
with a winding spindle, a continuously mov-
ing cam, a traverse slide reciprocated by the
35 cam, and a winding guide connected with
the traverse slide, of means to stop the
winding spindle and means to concurrently
disconnect the winding guide from the trav-
erse slide, to stop the winding.

40 4. In a winding machine, the combination
with a winding spindle and continuously ro-
tating cam, of a traverse slide continuously
engaging the cam, a guide coöperating with
the winding spindle and a guide carrying
45 device therefor coupled to the traverse slide,
means to stop the winding spindle and
means to concurrently uncouple and stop
the guide carrying devices.

5. In a winding machine, the combination
50 with a continuously moving cam, a winding
spindle and transmission mechanism con-
necting it with the cam, of a reciprocating
winding guide, actuated by the cam through
a coupling, means to uncouple the guide
55 from the cam; a frame which actuates the
said means to uncouple the guide, and also
acts to stop the winding spindle, means
through which said frame acts to stop the
winding spindle, and a yarn controlled
60 knock-off on the frame which, when released
by the yarn, engages the cam and is acted on
thereby to swing said frame for the purpose
described.

6. In a winding machine, the combination

of a single cam with a plurality of normally 65
stationary winding units, including winding
spindles and winding guides, means for au-
tomatically stopping the action of a unit,
and means for automatically causing the
presentation of the inactive unit at a given 70
point, and means to stop movement of the
unit when presented.

7. In a winding machine, the combination
with a single cam and a plurality of wind-
ing units, each including a winding spindle 75
and a winding guide; of means for auto-
matically stopping the action of a unit, and
means for automatically presenting and ar-
resting the inactive unit at a given point.

8. In a winding machine, the combination 80
with a plurality of winding units each com-
prising a spindle and coöperating guide,
said units being constantly impelled to re-
volve about the axis of the machine, of a de-
tent to restrain the said units from revolv- 85
ing, means to automatically release the de-
tent to permit revolution of the winding
units, a stop to arrest such revolution, and
means to engage the stop.

9. In a winding machine, the combination 90
with a plurality of winding units comprising
spindles and coöperating guides, said
units being constantly impelled to revolve,
of a detent to restrain said units from re-
volving, yarn controlled means to automatic- 95
ally release the detent upon discontinuance
of the yarn supply of any unit to permit all
the units to revolve to present the aforesaid
unit at a predetermined position, and a stop
to arrest the unit at that predetermined 100
position.

10. In a winding machine, the combina-
tion with a winding unit, comprising a spin-
dle and coöperating guide radially disposed
relative to the axis of the machine and con-
stantly impelled to revolve about the said 105
axis, and means to actuate the unit, of a de-
tent to withhold the unit from revolving
and maintain it operative in one position,
means normally withheld by the continuity 110
of the unit's yarn supply from acting on the
detent and released by the discontinuance
of said supply, to permit the unit to revolve
to a predetermined position for renewing
the yarn supply, and means to release the 115
unit from said predetermined position and
permit it to revolve to a new position.

11. In a winding machine, the combina-
tion with a cam, a guide reciprocated by the
cam, a winding spindle driven coöperatively 120
with the guide and cam, and means to effect
such coöperative action, of means to stop the
guide and spindle, comprising a swinging
frame swingable to effect the stopping ac-
tion, a "knock-off" coöperative with the 125
cam, withheld therefrom by the continuity
of the supplied yarn, and released, by dis-
continuance of the yarn, to engage and co-

- operate with the cam to swing the frame, and a supplemental device to further swing the frame to remove the "knock-off" from engagement with the cam.
- 5 12. In a winding machine, the combination with a cam, a guide reciprocated by the cam, a winding spindle driven coöperatively with the guide and cam, and means to effect such coöperative action, of means to stop the spindle, comprising a swinging frame, movable to effect the stopping action, a "knock-off" to coöperate with the cam, withheld therefrom by the continuity of the supplied yarn, and released by the discontinuance of the yarn to engage and coöperate with the cam to swing the frame, and a supplemental device to further swing the frame to remove the "knock-off" from engagement with the cam.
- 10 13. In a stop device for a winding machine, the combination with a winding spindle and guide and means to coöperatively drive them, including a cam, of a swinging frame, swingable to stop the spindle and guide and means through which the frame acts to effect such stopping, a knock-off cam, normally restrained from action during the operation of the spindle and guide, means to impel action of the knock-off cam, and a "knock-off", withheld from action by continuity of the yarn supplied and released by discontinuance of said yarn supply, to coöperate with the cam to swing the frame to stop the guide and spindle and release the knock-off cam which acts to further swing the frame to withdraw the "knock-off" from the cam.
- 15 14. In a winding machine, the combination with a winding spindle and coöperative guide, of a movable frame that by its position permits or prevents the operation of said spindle and guide, means to withhold the frame from permitting such operation, and a starting handle carried by the frame to control the said withholding means.
- 20 15. In a winding machine, the combination with a winding spindle and coöperating guide, of a movable frame that by its position permits or prevents the operation of said spindle and guide, a spring actuated means to withhold the frame from permitting such operation, a starting handle carried by the frame connected with the withholding device, and an arm connected with the starting handle and engaging an inclined portion of the frame, coacting therewith to raise the handle and retract the withholding device upon turning of the handle to release the swinging frame.
- 25 16. In a winding machine, the combination with a plurality of circularly disposed winding spindles revoluble about a common axis, a cam concentric with that axis, a guide operating with each spindle and means to coöperatively drive said spindles, cam and guide, of a stop to arrest the revolution of the spindles, means to stop the coöperative action of each spindle with the cam, including a movable frame, a "knock-off" to move the frame, a means to hold the frame from return, a slideable rod on which the withholding means is maintained which, when the aforesaid frame is moved, is projected into position to engage the stop and means to automatically project the rod and actuate the withholding means.
- 30 17. In a winding machine, the combination with a plurality of circularly disposed winding spindles revoluble about a common axis, a cam concentric with that axis, a guide coöoperating with each spindle, and means to coöperatively drive said spindle, cam and guides, of a stop to arrest the revolution of the spindles, means to withdraw each spindle from coöperative action with the cam, including a movable frame, a brake to stop the action of the spindle, a "knock-off" to move the frame, a means to withhold the frame from return, said means being connected with the brake, a slideable rod to concurrently move the withholding means and brake, which rod, when the aforesaid frame is moved, is projected into position to encounter the stop, and means to automatically operate the rod.
- 35 18. In a winding machine, the combination with a cam, and a traverse slide continuously reciprocated by the cam, of a guide and connections between it and the traverse slide including a spring latch, a wiper adjacent the path of travel of the traverse slide and spring latch, a movable frame to which the wiper is connected, and means to automatically shift the frame to engage the wiper with the latch to disconnect the guide from the traverse slide.
- 40 19. In a winding machine, the combination with a shaft, a cam mounted free on the shaft and stands ranged about the cam carrying winding guides driven by the cam and winding spindles connected with and driven by the shaft, of a cap mounted on the stands having a bearing for the shaft, a gear fast on the shaft and an internal gear fast in the cam, and a train of gears carried by the cap, connecting the shaft gear with the internal gear of the cam to drive the cam from the shaft in coöperation with the winding spindles.
- 45 20. In a winding machine, the combination with a cam, of a winding unit having a guide traversing device engaging and operated by the cam, means to automatically revolve the winding unit about the axis of the cam, and means to operate the cam and winding unit in conjunction.
- 50 21. In a winding machine, the combination with a cam, of a plurality of winding units, each having a guide traversing mechanism engaging and driven by the cam, auto-
- 55 60 65 70 75 80 85 90 95 100 105 110 115 120 125 130

matic means for revolving the winding units about the axis of the cam and means to operate the cam and winding units in conjunction.

5 22. In a winding machine, the combination with a system of winding units all influenced to revolve about an axis, of a single detent to prevent such revolution of all the units, and releasing means operative
10 by any one unit to cause the revolution of all the units.

23. In a winding machine, the combination with a winding unit which comprises with the winding spindle and co-operating 15 guide, a movable frame and an arm in the frame, the said unit being constantly influenced to revolve, of a detent to prevent such revolution and a connection between the detent and the aforesaid arm which on 20 shifting of the movable frame moves with the arm and acts upon the detent to release it to permit revolution of the winding unit.

24. In a winding machine, the combination with a cam and winding units, each unit including a swinging frame and an arm on the frame, all the units being influenced to revolve about the axis of the cam, of a detent to prevent such revolution and a position pin engaged by the detent, and an oscillatable ring, engaging the detent and the arms of all the units, through which the swinging of the frame of any unit acts to release the detent and permit revolution of all the units.

35 25. In a winding machine, the combination with a bed, a cam, concentrically disposed winding units, each including a swinging frame, a table on which the units are mounted, which table is constantly influenced.

40 to turn, of position pins mounted in the bed, a detent in the table normally in engagement with one of the position pins, and means whereby movement of any one of the swinging frames releases the detent from

45 its pin, and permits the table with all the winding units to revolve.

26. In a winding machine, the combination with a stationary bed, a cam, and winding units disposed about the cam, and each unit operated in part by the cam, of a table having a constant tendency to turn, on which table the winding units all are mounted, a plurality of position pins stationary in the bed, a single detent mounted on the table and engaging one of the position pins, and means to automatically release the detent, permitting the table to turn the winding units to a new position, the detent subsequently engaging another position pin.

60 27. In a winding machine, the combination with a stationary bed, a cam, winding units disposed about and operated in part by the cam, each unit including a swinging frame, and other means acting in conjunction with the cam to drive the units, of a

table having a constant tendency to turn, on which table the winding units are mounted, a single detent mounted on the table, a plurality of position pins stationary in the bed, yarn controlled means in each frame which when released causes the frame to swing away from the cam, and connections through which the frame in swinging acts to release the detent and permits the table to turn, carrying with it all the winding units.

28. In a winding machine, the combination with the bed 10 a table 17 superposed thereon, stands 18 mounted on the table and a cap 24 mounted on the stands, of a vertical shaft 22 having bearings in the table and cap, a friction driving wheel secured to and rotatable with the shaft, a cam rotatable on the shaft, spindles driven from the friction driving wheel and co-operating guides driven from the cam, and transmission connections 30 between the shaft and the cam. 35

29. In a winding machine including winding spindles, reciprocating guides and a cam to actuate the guide, the combination with a table 17, stands 18 secured thereto on which are connected the spindles and guides, of a cap formed with bearings, a shaft 22 extending through the table the cam and the cap, a spur gear 28 in the shaft and an internal gear 32 in the cam, an intermediate shaft 33 in one of the bearings of the cam carrying a gear 31 to engage the cam's internal gear and a spur change gear 30, an idler change gear 29 and its stud 35 having variable positions to accommodate the change of gear 1, and means to drive the machine through the shaft 22.

30. In a winding machine, the combination with the winding spindle, cam and operative connections between the cam and 105 winding spindle, of a traverse slide continuously reciprocated by engagement with the cam, a guide to coöperate with the winding spindle and connections between the guide and traverse slide including a latch, 110 a wiper adjacent the path of travel of the traverse slide and means to automatically present the wiper to encounter and disconnect the latch.

31. In a winding machine the combination with the winding spindle, cam and operative connections between the cam and the winding spindle, of a traverse slide having a ward and continuously reciprocated by engagement with the cam, a guide to co-operate with the winding spindle and connections between the guide and traverse slide including a latch which normally engages the traverse slide by its ward, and projects outside of the ward, a wiper adjacent the path of travel of the transverse slide but outside the path of travel of the projecting portion of the latch, and means to engage the wiper and latch to disconnect the guide from the traverse slide. 130

32. In a winding machine, the combination with the winding spindle, cam and operative connections between the cam and the winding spindle, of a guide coöperating with the winding spindle and a latch, a traverse slide engaging the cam and constantly reciprocated thereby, the traverse slide being formed with a ward and inclined surfaces leading to the ward, and means to shift the latch into the path of travel of the traverse slide to engage one of the inclined surfaces and enter the ward, to connect the traverse slide and guide.

33. In a winding machine, the combination with a constantly rotating cam, of winding units connected with the cam and impelled, through such connection to revolve with the cam's rotation, and means to normally restrain the winding units from revolving.

34. In a winding machine, the combination with a constantly rotating cam, of a plurality of winding units connected with the cam and impelled through such connection to revolve with the cam's rotation, means to normally restrain the winding units from revolving, automatically operated means to release the units and permit them to revolve and a stop to arrest such revolution at a predetermined point.

35. In a winding machine, the combination with a moving member, a winding spindle and coöperating guide, of a movable frame that by its position permits or prevents the operation of said spindle and guide, a spring actuated means to withhold the frame from permitting such operation, a starting handle carried by the frame and connected with the withholding device, a

thread controlled "knock-off" carried by the frame, which "knock-off", when released, engages the moving member, and through which the moving member acts to move the frame to the position in which it is controlled by the withholding means, the "knock-off" having an arm 68 with a curved off-set 95, and an arm connected with the starting handle and engaging an inclined portion of the frame, coacting therewith to raise the handle and retract the withholding device upon turning the handle to release the movable frame, the said arm also and concurrently engaging the curved off-set 95 of the arm 68 of the "knock-off" to withhold the latter from engaging the moving member until its controlling thread is taut.

36. In a winding machine, the combination with the winding mechanism and the start and stop mechanism, of a thread controlled "knock-off" which acts, when released, upon the start and stop mechanism with stopping effect and connecting means therefor, a starting handle to act upon the same mechanism with starting effect and connections therefor, an arm connected with the starting handle which is disconnected from and out of the path of action of the "knock-off" while the winding machine is in normal operation, but which is moved by the handle, in starting, to obstruct the "knock-off" and withhold it from action until the controlling thread is taut.

In testimony whereof I affix my signature in presence of two witnesses.

SIMON W. WARDWELL.
